HENRY MORTON, OF WOOD BAY, MANITOBA, CANADA.

GRAIN-CLEANING MACHINE.

1,393,154.

Specification of Letters Patent. Patented Oct. 11, 1921.

Application filed July 6, 1920. Serial No. 394,388.

To all whom it may concern:

Be it known that I, HENRY MORTON, of the village of Wood Bay, in the Province of Manitoba, Canada, have invented certain new and useful Improvements in Grain-Cleaning Machines, of which the following is the specification.

The invention relates to improvements in grain cleaning machines and the general object of the invention is to provide a machine which will effectively clean grain, separating the foreign material such as chaff, twigs, the undesirable weed seeds and wild oats from the wheat and which is arranged such that the wheat is collected on a conveyer at the back of the machine from which it can be readily elevated or bagged.

A further object of the invention is to arrange the screens so that they can be readily changed or substituted to accommodate the machine to the work in hand and also to construct a comparatively large capacity machine which can be readily driven either by hand or motor power.

A still further object of the invention is to arrange the machine so that it is of a comparatively narrow width, thereby allowing it to pass through the usual barn doors met with and also to arrange the drive in a convenient manner.

With the above more important and other minor objects in view, which will become more apparent as the description proceeds, the invention consists essentially in the arrangement and construction of parts hereinafter more particularly described and later pointed out in the appended claims, reference being had to the accompanying drawings in which:—

40 Figure 1 is a front view of the machine.
Fig. 2 is an end view thereof.

Fig. 3 is a rear view.

Fig. 4 is a vertical sectional view transversely through the machine.

45 Fig. 5 is an enlarged vertical sectional view longitudinally through the machine.

Fig. 6 is an enlarged detailed side view of one of the screen fastening hooks and other associated parts.

50 In the drawings like characters of reference indicate corresponding parts in the several figures.

1, 2, 3 and 4 represent upright equal length corner posts which are suitably connected by bottom sills 5 and 6 and suitably

disposed front, rear and end brace beams 7 and 8, 9 and 10, 11, 12 and 13, and 14.

The above parts constitute a substantially rectangular rigid frame which carries the driving parts and within which I locate a shoe later described.

At the top of the main frame I locate a hopper 15 which is adapted to feed forwardly to an outlet opening 16, the feed through the outlet opening being controlled by a sliding gate 17 which is adjusted by manipulating a pair of cranks 18 and 19 located at the back of the machines and extending from nuts 20 and 21 screw threaded on the outer ends of adjusting rods 22 and 23, the said rods having their inner ends attached to the gate and their outer ends passing slidably through bearings 24 and 25 attached to the cross brace 10.

At the front of the machine I locate a fan 75 casing 26 in which a fan 27 operates, the fan being mounted on the fan shaft 28 carried by suitable bearings 29 and 30 located on the front corner legs. The fan casing opens to the interior of the frame so that the blast 80 therefrom is directly through the grain which is being operated upon by the upper part of the shoe. The fan shaft is provided at one end with a pinion 31 adapted to mesh with the driving gear wheel 32 rotatably 85 mounted on one end of the machine and provided with a hand grip 33. The opposite end of the fan shaft is supplied with a bevel pinion 34 which is meshed with a bevel pinion 35 located on the end of a countershaft 90 36 carried by suitable bearings 37 and 38 located at one end of the machine.

The latter shaft is fitted with two pulleys 39 and 40 and the pulley 39 is connected by a belt or such like 41 to a pulley 42 secured 95 to a crank shaft 43 provided with a pair of cranks 44 and 45 and having the ends suitably mounted in bearings 46 and 47 carried by the end of the machine. The cranks both extend in the same direction from the shaft.

Toward the bottom of the frame and at the ends I locate two conveyer shafts 48 and 49 which are carried by bearings 50 and 51 secured to the corner legs. The conveyer 105 shafts are provided with pulleys 52 and 53 and the pulley 52 is connected with a belt or such like 54 to a pulley 55 secured to the adjoining end of the crank shaft.

At the front of the machine the shafts 110

are fitted with rollers 56 and 57 which carry a horizontally disposed endless belt 58 supplied with cross flats 59. The upper side of the belt operates over the bottom 60 of a trough 61 passing from end to end of the machine.

According to the driving arrangement shown the belt 54 will effect the driving of the conveyer in the direction indicated by the 10 applied arrow Fig. 1 assuming the gear wheel 32 is rotated in the direction indicated by the applied arrow in Fig. 2.

However if it should be more convenient for bagging or loading purposes one can reverse the direction of travel of the conveyer by removing the belt 54 and utilizing a cross belt between the pulley 55 and the pulley 53. Here I might mention that there is hardly room for a cross belt between the pulleys 52 and 55 and for this reason the pulley 20 53 is provided.

While I have entered into a detailed description of the driving arrangement it will be apparent that this could be readily modified without departing from the spirit of the invention. It will be observed that all the 25 parts herein before disclosed are carried by the frame structure.

Within the frame I locate a substantially 30 rectangular box like shoe 62 which has closed ends 63 and 64 connected by front guide beams 65 and 66 and rear guide beams 67 and 68 and is fitted on the underside with supporting guide beams 69 and 70. The bottom 35 guide beams 69 and 70 ride continuously on rollers 71 suitably carried by the sills 5 and 6, there being three rollers shown for the purpose in the drawings.

The guide beams 65 and 66, 67 and 68 operate 40 against front and rear sets of vertically disposed rollers 72 and 73 which have their ends suitably mounted in bearings provided in the sills 5 and 6 and the beams 7 and 9 of the frame.

To one end of the shoe I attach bearings 45 74 and 75 which carry a cross shaft 76 and the said cross shaft is connected to the cranks of the crank shaft by crank rods 77 and 78. Obviously from this arrangement the shoe 50 will be given a forward and back endwise shifting movement in the turning of the cranks and in this movement is entirely guided by the rollers.

Sets of cushioning springs 79 and 80 are 55 located between the ends of the shoe and the main frame. The shoe structure is strengthened also by front and rear sets of tie rods 81 and 82 passing between the ends of the shoe and provided with adjusting nuts for 60 tightening purposes.

Within the shoe and carried thereby I locate a plurality of screens 83, 84, 85, 86, 87 and 88, the screens 83, 85 and 87 being parallel and inclining downwardly in passing 65 from the front to the rear of the machine,

while the screens 84, 86 and 88 are parallel and incline downwardly in passing from the rear to the front of the machine.

Beneath the screens 84, 85, 86, 87 and 88 I locate parallel collecting pans 89, 90, 91, 92 70 and 93 which incline downwardly toward the back. The selection of these screens is such that when say wheat is being cleaned from chaff, twigs, wild oats and weed seeds the action will be as follows:—

The mixed grains fall from the hopper on to the top screen 83 which is of a mesh such that the wheat, small seeds and other small particles of foreign material will fall through the screen while the larger material 80 such as chaff, twigs and possibly wild oats will be thrown over the front end of the screen. At the screen 84 the seeds and other small material go through and are caught by the pan 89 which passes them off through 85 the back of the machine.

The grain caught on the screen 84 is passed forwardly over on to the screen 85 where the good grain and small seeds go through on to the pan 90 and the other larger 90 material is thrown over at the back. The material sliding off the rear end of the pan 89 is then caught by the screen 86, the small seeds going through and being thrown out by the pan 91, while the grain is passed over 95 the end of the said screen on to the screen 87 where the grain goes through and the larger material like oats are thrown over.

The grain passing through the screen 87 is caught by the pan 92 and passed back by it 100 to the back end of the screen 88 where a final separation is made, the cleaned wheat being delivered by this screen to the conveyer at the front of the machine, while the remaining small seeds and other foreign material is 105 caught underneath by the pan 93 and thrown out the back of the machine.

As the shoe is reciprocated backwardly and forwardly in the frame by the action of the cranks and the screens and pans are all 110 inclined the grain is actually gradually fed from the top of the shoe to the bottom, the separation taking place as it goes down until finally a particularly efficient cleaning is effected and the cleaned wheat is delivered 115 on to the conveyer.

Here I may state that I propose utilizing this machine with any of the well known forms of baggers or elevators which can be positioned at either end of the conveyer according to the conditions met with and can be driven if desired from a pulley (not shown) secured to one or other of the conveyer shafts which are extended as best shown in Figs. 2 and 4, for this purpose.

Further, the screens are of the ordinary form and are fitted within the shoes so that they can be readily withdrawn and interchanged or others substituted.

In the present instance the ends of the 130

screens are received between spaced cleats 94 and 95 secured to the ends of the shoe and are held in place by pivoted hooks 96 attached to the ends of the shoe and adapted 5 to pass into suitable registering openings supplied in the cleats and screen ends.

In connection with the removal of the screens which are taken out of the back of the machine, I may say that it is necessary 10 to have the bearings for the back rollers arranged so that they can be quickly undone to permit of the dismounting of the rollers and the subsequent withdrawing of the screens.

15 I wish also to point out that when the machine is in action the blast of air from the fan is operating on the screens in the upper part of the shoe and is acting to blow, by an air blast, all the light material back- 20 wardly and out the front of the machine, thereby effecting a considerable initial separation.

I wish to point out also that the arrangement of the machine is such that it readily 25 lends itself for machines in various sizes and in this connection I may state that the machine is increased in length rather than width as I desire particularly that the width of the machine be maintained such that it 30 can be at all times passed through the existing doors which one finds in a barn.

Obviously the machine can be power driven by connecting a pulley to the gear wheel 32.

35 In order to allow the screen 88 to move with the shoe I have cut parts of it away at 97 to clear the rollers and have placed V-shaped strips 98 on the top side of said screen to deflect the cleaned grain as it 40 passed the rollers and direct it out to the trough.

What I claim as my invention is:—

1. In a grain cleaning machine, a supporting and guiding structure for a reciprocable 45 grain shoe comprising opposing sets of vertically disposed guide rollers engageable with opposite sides of a shoe and horizontally disposed supporting rollers extending entirely across the space between the two 50 sets of vertical rollers and at the lower ends of the latter.

2. In a grain cleaning machine, the combination with a reciprocable grain shoe comprising spaced end plates and guide bars extending between and connecting the side 55 and lower edges of said plates, of a supporting and guiding structure for the shoe comprising a frame, opposing sets of vertically disposed rollers journaled in said frame and engageable with the guide bars connecting 60 the side edges of the shoe plates, and a horizontally disposed set of rollers extending entirely across the bottom of the frame and providing a support for the guide bars connecting the lower edges of the shoe plates. 65

3. A grain cleaning machine including a frame comprising opposing sets of vertically disposed rollers forming opposite sides of the frame and horizontally disposed rollers extending between the vertical rollers and 70 forming the bottom of the frame, a screen shoe reciprocable in said frame arranged to be guided and supported by said rollers, said shoe comprising a plurality of superimposed screening plates and collecting pans 75 arranged one beneath each screening plate, one of said screening plates having its discharge end projecting beyond one side of the frame and notched to accommodate the vertical rollers located at that side of the frame. 80

4. The combination with the structure recited in claim 3, of a trough carried by the frame beneath the projecting end of the notched plate, and a conveyer operating in 85 said trough.

5. The combination with the structure recited in claim 3, of deflecting means carried by the notched plate for deflecting the material passing toward the discharge end of the plate away from the notches. 90

6. An arrangement according to claim 3, in which the screens of the shoe are removable and in which certain rollers of the frame may be dismounted to permit such removal of the screens. 95

Signed at Wood Bay, this 15th day of May, 1920.

HENRY MORTON.

In the presence of—

JOHN PONCH,
JOHN C. WATSON.
